Josiah St. John
Spelters Patent

The schedule referred to in this Letters Patent and making part of the same containing a description in the words of the said Josiah St. John himself of his improvement in tin or other metal bakes.

To all to whom these presents shall come
Be it known that I Josiah St. John of the City of Hudson in the
County of Clinton and State of New York have invented a
new and useful ^{improvement} in tin or other metal bakes and that the following
is a full and exact description of the construction and operation of
said bakes as improved by me. This bake may be made of tin,
sheet iron or any other metal and of any convenient size or
shape. For the better understanding it suppose one construc-
tion of tin of the following shape and dimensions. The body in
which is the oven, two feet in length by one foot in height and width
with a door on the side in front. On either end a projection for the
furnace in a circular form eight inches in length and nine inches
in height; with a circular opening in the top of six inches in di-
ameter in which to set the teakettle or other boiler. In each end
is placed the furnace (a.u.ye.) cone shaped with a grate at
the bottom, on which the coal or other fuel lies and under each fur-
nace (E.C.30) is an ash pan. Over and fitted round the top of the
furnace is a dam (b.b.ye.) over which or rather into the top of
which the boiler (P.S.) is placed, and from the side of which leads
the flue or chimney (C.C.30) either out at the top of the bake in
which case an additional oven may be put on the top and heat
from the flue or chimney, or the flue or chimney may be lead out
at the back of the projection on end of the bake which said projec-
tion as and may ^{be} square or round and the top of it depressed
as above or level with the top of the bake and convenient on table
may situate. Note the top of the flue or chimney is fitted a clam-
per

St. John

heat (or, &c.) by which the heat in the oven may be more regulated. On the oven and near each furnace stands a plate of sheet iron not extending to the sides all around (fig. 3c) for the purpose of heating and equalizing the heat of the furnace in the oven. On the sides of these plates are made convenient places for putting in horizontal rods (h. h.) upon which to set the necessary vessels used to bake in. The baker stands on legs (ff, 8) and has a pair of handles or rings fixed into the top to lift and remove it by. The furnace may be round or square and the whole of almost any shape or size to suit the buyer. Now what I claim is my invention or improvement in the tin or other metal baker is First the boiling or heating of liquids as well as baking at the same time and with the heat of the same fuel. And Second by the combination and application of so much of the known parts and principles of machinery, not before combined and applied in regard to the said baker as are necessary to produce the double effect aforesaid. to wit, that of boiling and baking at the same time, as aforesaid
